UNITED STATES PATENT OFFICE.

EDMUND C. MORGAN, OF CHICAGO, ILLINOIS.

MINING-MACHINE.

1,116,354.

Specification of Letters Patent.

Patented Nov. 3, 1914.

Application filed August 4, 1905. Serial No. 272,637.

To all whom it may concern:

Be it known that I, EDMUND C. MORGAN, a citizen of the United States, residing at Chicago, in the county of Cook and State 5 of Illinois, have invented a new and useful Improvement in Mining-Machines, of which the following is a specification:

This invention relates more particularly to that type of mining machines which are supported upon tracks or ways and driven 10 into the drift or tunnel by suitable power, usually mounted upon the machine itself, and serving at the same time as a means of operating the cutters or mining tools, and 15 the invention has for one of its objects to provide improved and efficient means whereby by the coal or other material to be mined is cut into slabs in the face of the drift or wall at the end of the tunnel, whereby the 20 slabs may be readily broken down and transferred to the rear, a further object in this regard being to provide a machine of this character which will first cut the kerfs or channels in the wall of the tunnel, necessary 25 for producing these slabs, and then wedge the slabs apart, causing them to break from the main body of coal, ore, or other material being mined.

Another object of the invention is to provide 30 improved and efficient means whereby a dirty vein, or vein of other objectionable substance, running through the vein of material to be mined, may be readily cut out of the vein of desirable substance and separated from the mined portion of the latter.

With a view to the attainment of these ends, and the accomplishment of certain other objects which will hereinafter appear, the invention consists in the features of 40 novelty in the construction, combination, and arrangement of parts, which will now be described with reference to the accompanying drawings, and more particularly pointed out in the appended claims.

In the said drawings, Figure 1 is a plan view of a mining machine constructed according to this invention. Fig. 2 is a view mostly in vertical section thereof, and partly in side elevation. Fig. 3 is a plan 50 section thereof. Fig. 4 is a detail transverse section of one of the sections of the way, showing also a portion of the truck or carriage and the traction gear, taken longitudinally of the forward axle. Fig. 5 is a similar section taken longitudinally of the 55 rear axle, showing the means for adjusting

the frame. Fig. 6 is a vertical section of a modification of one of the spiders for carrying the cutters, showing also the means for tripping the cutter arms, the extensions 60 63 and 65 being pivoted to the under side of the arms 52, 52 instead of the upper sides. Fig. 7 is an enlarged transverse section on the line 7-7 of Fig. 2 of one of the cutter arms and a portion of the cutter dove-tailed 65 therein. Fig. 8 is a detail perspective view of one section of the way. Figs. 9 to 12, inclusive, are sectional views of the channel in different stages formed in the wall of the ore or coal preparatory to the breaking- 70 down operation; and Figs. 13 to 16, inclusive, are elevations of the tools used, respectively, for producing these different stages of the cut. Fig. 17 is a sectional view of the channel, showing the manner in which 75 the slab is broken out after the final cut. Fig. 18 is an elevation of the wedge which does the breaking. Fig. 19 is a vertical sectional view showing a modification comprising means for the quick adjustment of 80 the cutter spiders. Fig. 20 is a plan view thereof, partly broken away. Fig. 21 is a still further modification thereof. Fig. 22 is a modified form showing an automatic means of actuating the tripping mechanism 85 for the cutter arms. Fig. 23 is a vertical sectional view thereof on the line 23-23. Fig. 22. Fig. 24 is a plan view of one of the spider arms and the cutter arm supported thereon, showing a modification of the means 90 of throwing the cutter into and out of position. Fig. 25 is a vertical longitudinal sectional view of a portion of the forward part of the machine, showing a certain modification in the means of supporting and actuating the cutters, and also showing an attachment comprising means for conducting the material removed from the dirty vein to the rear and keeping it separate from the material being mined. Fig. 26 is a plan section 95 thereof taken in a plane just above the upper one of the dirty vein cutters.

1 represents the supporting wheels of a carriage or truck, having axles 2, 3, running on a track or way comprising rails 4, 5. 100 These rails 4, 5, are formed at the sides or ends of short blocks or sections 6, which are placed in continuously advancing series as shown in Fig. 2, and if desired may have interlocking tongues 7 and grooves, so that 105 when properly positioned with respect to each other they will constitute a continuous

track or way. These sections are comparatively narrow or short with respect to the length of travel of the machine, so that as the machine proceeds into the tunnel or drift, the sections which the wheels 1, 2, have left in the rear, may be taken up and placed in advance of the wheels in front, thus requiring but a comparatively few number of these members. They are also 5 formed with rack-bars 8 extending longitudinally thereof or parallel with the rails 5 and in line with each other, so as to constitute a continuous rack for the engagement of a traction gear 9 secured to the forward axle 10 15 2 and serving for the propulsion of the machine, the bottoms of the sections of the way being provided with spurs 10 for preventing them from slipping rearwardly, and if desired this rearward motion may also be 20 further guarded against by the employment of one or more jacks, as shown in Fig. 3, comprising two members 11, 12, having screw-threaded connection with a third member 13, thereby constituting a means of forcing the member 12 against a lug 14 or socket on the side of the section 6, and the member 12 against the wall of the tunnel.

The forward axle boxes 15 are secured to or formed on side members 16 of the main frame, while the rear axle boxes 17 are mounted in vertical slots 18 in said side members 16 of the main frame, and these side members are supported upon the boxes by means of vertical screws 19, which have 30 35 40 45 50 55 60 65 70 75 80 85 90 95 100 105 110 115 120 125 130 135 their upper ends screw-threaded in the frames 16 and their lower ends stepped upon the boxes 17. By rotating these screws, the entire main frame, supported by said side members 16 thereof, may be adjusted in a rotary direction around the forward axle 2, without interfering with the proper engagement of the traction gear 9 with the rack 8. These screws 19 may be rotated, for thus adjusting the frame, by any suitable means, as, for example, worm wheels 20 secured one to each of the screws 19, and each having an engaging worm 21 mounted upon the adjacent box 17 in any suitable way, and if desired these worms may be connected together by sprockets 22 and chain 23, so that by the rotation of either crank 24 on the worms 21 the two screws 10 may be simultaneously rotated for producing the aforesaid adjustment, the purpose 55 60 65 70 75 80 85 90 95 100 105 110 115 120 125 130 135 of which is to tilt the cutting mechanism at the proper angle for changing the direction of cut to suit the run of the vein, as will be hereinafter described.

The traction gear 9 derives its propelling power from any suitable source, as, for example, an electric motor 25 mounted directly upon the machine, and having bevel-gear connection 26 with a perpendicular shaft 27, at or near the lower end of which is secured 65 a worm 28, engaging two worm wheels 29,

60 arranged on opposite sides thereof, and running loosely upon two horizontal shafts 31, 32, respectively. The shaft 32 has a bevel pinion 33' engaging a bevel gear 34' on a sleeve 35, forming a part of, or secured to, the traction gear 9. This shaft 32 also has splined upon it a clutch member 33, capable of being shifted by a lever 34 into engagement with a clutch member 38 on the worm wheel 30, so that when desired the shaft 32 may be rotated in the proper direction for driving the machine into the tunnel. When it is desired to withdraw the machine, or reverse its direction of motion, the shaft 31, which is connected by a bevel gear 36 to a bevel pinion 37 secured to the axle 2, is connected with the worm wheel 29. This is accomplished by a similar means, namely, a clutch member 38, which is splined on the shaft 31 and adapted to engage a clutch member 39 secured to or formed on the worm wheel 29, clutch member 38 being provided with a shifting lever 40 for facilitating its described operation. It will be seen, therefore, that the rotation of the shaft 31 by the worm 28 will impart a reverse rotation to the axle 2.

At the rear of the clutch 35 is an additional clutch 200 and at the rear of the clutch 39 is an additional clutch 201. The fixed members of the clutches 200 and 201 are mounted in the cross-piece 42. The clutches 200 and 201 are for the purpose of holding the truck against movement when any such tendency manifests itself. Therefore, when the truck has been moved to the proper position, it will be held in adjusted position by means of the clutches 200 and 201. These various parts of the machine, which are carried by the truck and are adjustable, together with the side members 16 of the main frame, may be supported on the main frame in any suitable way. For example, the motor casing may be connected directly with the side members 16, while the shafts 31, 32, are journaled in cross-bars 41, 42; and for the purpose of carrying the cutting mechanism and its power-transmitting devices, which will now be described, the frame is provided with longitudinal extensions 43, 44, arranged near the top and bottom thereof, respectively, and secured to the side members 16. Journaled in the ends of these frame extensions 43, 44, is an upright shaft 45, upon which are secured a plurality of hubs 46, 47, 48, constituting parts of the spider frames which support and rotate the cutters and breakers, as will be presently explained. Intermediate ones of these hubs 47, 47, are formed with rigid or integral arms 49, four of which, in this example of the invention, are employed on each of said hubs, and alternating with the arms 49 are shorter integral or rigid arms 50, 51, 52, 53, while the hubs 46, 48, at the upper and lower 135

ends, respectively, of the upright shaft, are provided with flexible or hinged arms, connected thereto by means of pivots 54, so as to be capable of rotating or oscillating in perpendicular planes, or planes extending longitudinally of the shaft 45, whatever its position be, so that as the hinged arms turn away from the face of the tunnel or entry they may be moved away from the top and bottom of such entry to prevent engaging therewith when the machine is tipped or adjusted on the front axle 2, as before explained. The top series of these hinged arms lower out of the way of the top of the tunnel by gravity, and are held in their horizontal or operative position by a cam 54^a mounted upon the extension 43, while the lower series of these hinged arms, or those carried by the hub 48, fall into operative position by gravity, and are lifted away from the bottom of the tunnel by any suitable cam 54^b, supported in any suitable way, as by brackets 54^c on the under side of the frame extension 44, the arms of the lower series, or those connected to the hub 48, being limited in their descending movement by stops 54^d, of any suitable construction. There are two series of these hinged arms, a long series comprising arms 55, preferably four in number, and a short series alternating with the arms 55 and comprising arms 56, 57, 58 and 59. In the outer ends of the longer arms 49, 55, of all of these spiders, are mounted bits or cutters 60, of any appropriate form, but preferably the bifurcated form shown in Fig. 13, which is adapted to produce the first cut or kerf 61, shown in Fig. 9, as the arms 49, 55, swing around with the shaft 45, the thin fin of coal or ore 62 which is left between the bifurcations of the cutter 60 being broken down and crumpling away as the cutter arms 49, 55, advance into the kerf. In practice, this bifurcated form of the cutting end of the cutter is best produced by the employment of two separate cutters, one in the upper and one in the lower side of the spider arm, and which separate cutters may be dove-tailed in opposite sides of the spider arm, as shown in Fig. 7, for the sake of strength and simplicity of construction, but the particular form of cutter is immaterial so long as it is capable of producing a kerf or channel in the face or wall of the tunnel or drift. The shaft 45 is rotated a sufficient number of times to carry the arms 49 and 55, with the cutters 60, into the wall to produce the kerfs at the top and bottom of the tunnel, and at as many intermediate points between the top and bottom as there are spiders 47 employed, and when the kerf is formed a sufficient distance into the wall of the tunnel, the other cutters for producing the succeeding stages of the cut, shown in Figs. 10 to 12, and the breaker for wedging into the kerfs, are then

brought into successive operation, as will now be explained.

The arms 50 to 53 of the rigid spiders, and the arms 56 to 59 of the flexible or hinged spiders (which are the short arms in every instance), are provided with flexible extensions 63, 64, 65 and 66, respectively, which are hinged to their respective arms by the vertical pivots 67, whereby these extensions may be turned inwardly in horizontal planes toward the center of rotation of the spiders in order to carry the cutters or tools, mounted in such extensions, out of the way of the face of the tunnel while the cutters 60 are producing the first cut. These flexible extensions are rigidly secured to their pivots 67, and to the lower end of each of these pivots are rigidly secured two projections 68, 69, by means of which the flexible arms may be rotated with respect to the arms to which they are pivoted. This is done at the will of the operator by pushing or pulling on handles 70, 71, 72, 73, according to whether it is desired to throw the flexible arms into or out of cutting position. The handle 70 is connected to a rocking lever 74, pivoted on an extension 75 of the frame 43, and having two trips or pins 76, 77, which are alternately pushed upwardly through said extension 75 as the lever 74 is oscillated into the path of the extensions 68, 69, whereby one or the other of the pins 76, 77, will engage with one or the other of the extensions 68, 69, and rotate the flexible arm, to which said extensions are secured, into a position either at an angle to the main arm of the spider, as shown in Fig. 3 of the drawing, or into a position substantially straight or aligned with such arm, as shown in Fig. 1 of the drawing. When pin 77 is raised, the short extension 68 will be engaged, and thereby straighten out the flexible arm and cause the cutter thereon to enter the kerf and produce a portion of the lateral breaking groove 78 (see Fig. 12) formed in the opposed faces 110 of the kerf. The first one of these flexible arms to be thrown out on each of the spiders is the one carrying the form of cutter 79 shown in Fig. 14 for producing the portion of the breaking groove shown at 80 in Fig. 10. This cutter 79, like the cutter 60, may be formed in two pieces inserted, like the cutter 60, in opposite faces of its flexible carrying arm, such flexible arm being the one marked 63, which immediately follows the short flexible arm 59 of the top and bottom spiders and the short rigid arm 53 of the intermediate spiders; that is to say, it is the first one of the short arms to enter the kerf after all of the long arms have 125 gone around. As shown in Fig. 14, the cutters 79 are formed with angular or lateral extensions 79^a, which produce the portions 80 of the breaking groove, while not interfering with the fin or rib 62 left by the cut- 130

ters 60 at the inner side of the kerf. One revolution of the cutters 79 in each kerf will ordinarily be sufficient to produce its allotted portion of the breaking groove 78, and consequently after the arm 63 has passed out of the kerf it is again thrown back into its angular position with respect to the spider arm by the operator imparting a reverse movement to the handle 70, and in fact, to all of the handles, 70 to 73, one for each of the spiders, if it is desired to produce the breaking groove in all of the kerfs. This opposite movement of the tripping handle throws the pin or trip 76 up into the path of the extension 69, and returns the flexible arm into the position shown in Fig. 3, the extension 68 passing between the pins 76, 77, at that time. Each of the other handles, 71 to 73, inclusive, is provided with a tripping mechanism similar to the trip pins 76, 77, and rocking lever 74, one for each of the spiders. The rocking lever for the handle 71 is shown at 81, pivoted to the extension 43, and its tripping lugs at 82, 83. The rocking lever for the handle 72 is shown at 84, and its tripping pins at 85, 86, and this lever, together with the one for the handle 73, is pivoted to the extension 44, the latter lever being shown at 87, and its tripping pins at 88, 89. These are turned downwardly, while the pins for the lever 84 are turned upwardly, so that the former will trip the flexible arms belonging to the lower one of the spiders, of which the hubs 47 are parts, while the latter tripping pins 88, 89, will trip the flexible arms belonging to the lowermost spider, of which 48 is the hub.

It is evident that because of the nature of the framework of the machine the handles 72, 73 as well as those designated 70 and 71 are accessible from the sides of the machine. If the machine is particularly wide the handles may be reached by means of a rod or other device held by the operator.

The flexible arms 63 on all of the spiders having traversed their respective kerfs and being again thrown back into the angular position with respect to their spider arms, as shown in Fig. 3, the next flexible arm 64 on each of the spiders is thrown out into operative position in a manner similar to that described with reference to the arm 63 by the same tripping mechanism which operated upon the arm 63, and the additional portion 90 of the breaking groove or channel 78 is then produced by the lateral extensions 91 of the cutters 92 carried by these flexible arms 64, the only essential difference between the extensions 91 and the extensions 79^a being one of length, so as to cut the breaking groove a little deeper than the cut produced by the extensions 79^a. The arms 64 having passed around or fully traversed the kerf, they in

turn are thrown back again into the position shown in Fig. 3 by the trip mechanism before described, and the next flexible arms 65 in the series are then projected, in a similar manner to the operation of those already described, by a proper manipulation of the tripping handles, and the angular extensions 93 of cutter or bit 94 finish the formation of the breaking groove 78 by drawing the bottom or inner walls of the groove to an apex, as shown in Fig. 12, whereby the slab of coal or other material will break more readily along a definite line when the breaking-down wedge enters the kerf. This wedge is shown at 95, and is carried by the next one of the flexible arms in each of the series, the same being the arm 66, and it is thrown outwardly into operative position so as to enter the kerf, in the same manner that the other flexible arms are actuated. The wedge, as better shown in Figs. 17 and 18, is tapered in two directions; that is to say, in a direction lengthwise of the spider arm which carries the flexible arm 66, when the flexible arm is in its extended or operative position, and also transversely of this direction, with the narrower end of the wedge pointed in the direction of rotation, so that the wedge will more readily enter the kerf and by gradually forcing the walls of the kerf apart cause the slab of coal or other material to break down and fall out. If the wedge be tapered both top and bottom it will effect the breaking of the top slab as well as the bottom one, as shown in Fig. 17, but whether it be provided with this double taper or not will depend upon the character of the material being mined, in some instances a single taper being sufficient, where a wedge is employed on every alternate spider.

In order that the intermediate spiders may be adjusted vertically on the shaft 45 for changing the levels at which the cutters enter the wall, if desired the shaft in the vicinity of the hubs of these spiders is provided with a spline 95, over which the hubs slide, while being compelled thereby to rotate with the shaft; and the hubs are provided with set-screws 96, 97, or any other suitable means for holding them to their adjustment on the shaft. The shaft is supported against downward movement by the lower one of the hubs 47 taking its bearing upon the frame extension 44, or directly upon one or more shims 98 interposed under said hub when the latter is adjusted in a direction away from the frame 44; and if greater support than this be needed for the shaft, its lower end may be stepped on a bearing 99, which is in the form of a shoe, sliding upon the bottom of the tunnel, and formed on or secured to the cam 54^b, or given any other suitable connection or support on the frame of the machine.

The shaft 45 is rotated by the motor 25 through a suitable train of gears 100, 101, 102, the first of which is keyed to the shaft 45, and the last of which is mounted loosely upon the shaft 27, while the intermediate gear 101 is an idler mounted upon a stud-shaft 103 secured in cross-bars 104 extending athwart the machine and connected to the side frames 16. The gear or pinion 102 constitutes one member of a clutch, and is provided on its lower face with clutch teeth 105, adapted to engage with the companion member 106 of said clutch, which is connected by a spline 107 with the shaft 27, and is supported by a shifting yoke 108, capable of throwing it into engagement with the clutch teeth 105 when it is desired to rotate the cutter shaft 45. This shifting yoke may be actuated at the will of the operator by means of any suitable handle 109.

In the modification shown in Fig. 19, is provided a means of adjusting the spiders with greater facility than would be possible with the set-screw 96 or 97 already described. In this modification, the upper side of the spider is provided with two flanges 110, 111, under which engage two shoes 112 secured to the lower ends of two links 113 on diametrically opposite sides of the hub 47' of the spider, the upper ends of said links being pivoted, respectively, to the branches of a yoke 114, which is fulcrumed in a support 115 on frame extension 43, and has an arm 116 constituting in effect, with said yoke, a bell-crank-lever, the arm being connected to one end of a screw-threaded rod 117 passing through an abutment 118 on extension 43, and carrying adjusting nut 119 on the other side of the abutment.

In Fig. 21, a substitute for the pivoted arms of the spiders at the upper and lower ends of the shaft 45 is shown. This consists in making the shaft 45 hollow, or providing it at each end with a socket 45^a, and inserting therein a short section of shaft 45^b, upon which the hub 120 of the spider is rigidly secured, the shaft 45^b being splined in the socket 45^a and held at its vertical adjustment by a set-screw 121. In this form, the spider arms shown at 122 are illustrated as being adjustable longitudinally with reference to their hub 120, and held in place by set-screws 123. This modification avoids the use of the cams 54^a and 54^b and the hinged spider arms, because with this arrangement the lower spider may be elevated to carry it away from the bottom of the tunnel, and the upper spider lowered to carry it away from the top of the tunnel when the machine is to be backed out.

In Figs. 22 and 23 is shown an automatic means for shifting the trips which throw the flexible cutter and breaker arms into 65 and out of position. This comprises a box

cam 124, pivoted on a stud 125, and connected to the rocking lever 81, which actuates the trip lugs 82, 83, by means of rods 126, 127, connected together by a set-screw 128, and having a pin 129 running in the groove 70 of cam 124, the rod 126 having the handle 71, whereby the device may be actuated by hand if desired when set-screw 128 is released. The periphery of the cam 124 is provided with gear teeth 130, meshing with 75 a pinion 131 on the upper end of shaft 27, and if one of these automatic devices be provided for each of the spiders there will, of course, be as many as there are spiders, and the shaft 27 will be provided with as 80 many pinions 131 as there are cams 124 the single example shown in Figs. 22 and 23 being sufficient, however, for the purposes of illustration and an understanding of this 85 feature of the invention.

In the modification shown in Fig. 24, is illustrated a substitute for the flexible arms 63 to 66, which carry the series of cutters for producing the breaking groove 78 and the breaking wedge 94. This modification 90 consists in sliding the supplemental arm longitudinally of the spider arm which supports it, instead of deflecting such supplemental arm on a vertical axis, as is done with the supplemental arms 63 to 66. The 95 supplemental arm in this modified form is indicated at 132, and has a shank 133 sliding in the end of the spider arm, the one represented in this figure being the arm 50. The shank of the supplemental arm is provided with a pin or lug 134 engaging in a slot 135 of a shifting lever 136 pivoted to the arm 50, and so arranged as to be struck by one or the other of the trip lugs 82, 83, which are projected alternately down into 100 the path of the lever 136, as before described with reference to the projections 68, 69, the pin 83 serving to throw the supplemental arm 132 outwardly, and the pin 82 acting to withdraw it.

In Figs. 25 and 26 is shown a modification of the cutters and their carrying spiders, as well as an attachment for the machine whereby the dirty vein or objectionable stratum is removed separately from the desirable ore or coal. In Fig. 25 the shaft is shown as being provided at its upper and lower ends with the same form of spider and cutters as described with reference to Figs. 1 to 3, and one of the intermediate 115 spiders 47 in this view is also the same as the upper one of the intermediate spiders in the aforesaid figures, but in lieu of the lower one of the intermediate spiders, are substituted two spiders of special form comprising hubs 138 and arms 139. These spiders and their cutting mechanism are the same in construction, and hence the description of one will answer for both. Suffice it to say that they are reversed on the shaft 45 with re- 120 125 130 135 140

spect to each other. On the outer end of each of the arms 139 is pivoted a disk 140, which serves as a substitute for the flexible tool-carrying arms or supplemental arms 63 to 66, or the supplemental arm 132 shown in Fig. 24, four of these disks 140 being employed, and adapted to revolve on their pivots 141 in planes substantially parallel with the plane of rotation of the spiders 138, 139, the plane of rotation of one of the spiders being also parallel with that of the other. In the peripheries of these disks 140 are secured, respectively, the cutters 79, 92 and 94, and the breaker or wedge 94*. Secured rigidly to the shaft 45, so as to rotate therewith, is a disk 142, whose periphery is provided with circular orifices 143, in which the cutter disks 140 are situated and rotate, and this disk 142 is in substantially the same plane as the disks 140, and carries in its unbroken periphery, at as many points between the orifices 143 as desired, a number of the cutters 60, which, as the disk 142 rotates, produce a kerf the same in form as the kerf 61. The peripheries of the disks 140, however, being within the circle of the periphery of the main disk 142, the former disks will not effect the cutting of the wall excepting when the cutters mounted in the peripheries thereof are turned outwardly through the apertures 143. This rotation of the disks 140 for accomplishing that result is produced successively as the main disk 142 rotates in the same or substantially the same manner as the supplemental arms 63 to 66 or 132 are thrown into active position.

The arm 139 of each of the disks 140 has rigidly secured to it in any suitable way a ratchet 144, and pivoted to the disk is a spring-actuated pawl 145 arranged to engage this ratchet for preventing the disk from making a retrograde rotation as its cutting tool engages the wall of the tunnel. The cutting tool of the disk within the wall having traversed the kerf and performed its allotted function, however, the disk 140 is rotated a quarter turn in a direction away from its ratchet 144 when one of a series of lugs 146 on the face of the disk 140 engages one of the trip pins or lugs 82, 83, which may be thrown downwardly into the path of the lugs 146 at the proper time by the operator, as before described. When pin 83 is thrown downwardly it engages one of the lugs 146 at the inner side of the series, or next the shaft 45, and that causes the disk 140 to turn forwardly, or in the same direction in which it is revolving, thus carrying its cutter into the recess 143 and out of the way of the wall. When the pin 83 is thrown downwardly, however, the lugs 146 are engaged on the outer side of the series, and this restores the disk 140 to its former or operative position. The trip lugs or pins 82, 83,

are thus manipulated at the will of the operator as required for successively throwing the tools carried by the various disks 140 into and out of their operative positions, or, if desired, such manipulation may be done automatically by the construction shown in Figs. 22 and 23. An advantage of this form of spider and cutting mechanism is, that the main disk 142 and the smaller disks 140 constitute together a platform or revolving table on which to receive the material cut out and thrown down, and which by its rotation serves to conduct the material to the rear. In Fig. 25 of the drawing, these two table-like forms of cutters are illustrated as cutting out what is called the dirty vein, 147, which occurs in coal mines, and which may be constituted by ordinary dirt or soil, slate, or other material, the presence of which in the coal or substance being mined would be objectionable. The material cut out of the wall by these table-like cutters and thrown down thereon by the wedge or breaker, or by any other means, is carried around with the lower table or disk, on which it rests until it strikes a deflector or shield 148, which extends partially around the edge of the lower main disk 142 and terminates in a chute or trough 149. In this exemplification of the invention, this shield 148 is of sufficient height (as shown in Fig. 25) to practically close the space between the disks 142, so that all the material carried on the lower disk 142 will strike against the shield and be finally worked into the chute 149, whence it falls in the tunnel at one side of the machine. If the disk 142 rotates toward the right as viewed in Fig. 26, assuming the left-hand side to be the forward end of the machine, the shield or deflector 148 should be located on what would be the right-hand side of the machine, while the chute 149 should be located on the opposite or left-hand side, so that while the coal or valuable material is passed out on the right-hand side by the other cutters, or by the sweep of the bottom spider arms, the dirty material will be thrown out on the opposite side and kept separate from the material of value.

The spiders 138, 139, are adjustable vertically on the shaft 45, so that the cutters carried thereby may be arranged at elevations to suit the position of the vein to be cut out, and when so adjusted they may be fixed in place by set-screws 150, or any other suitable devices, 151 being a collar fixed to the shaft 45 by a set-screw 152, if desired, for affording better support for the upper one of the spiders 138.

Claims.

1. In a machine for the purpose described, the combination of means for cutting kerfs in the mine wall, and means for cutting lateral breaking grooves at the inner edges of

the kerfs at an angle to the planes of their opposed sides, whereby the slabs between the kerfs may be broken down.

2. In a machine for the purpose described, the combination of means for cutting kerfs in the mine wall, and a succession of cutters of different sizes for cutting lateral breaking grooves at the inner edges of the kerfs at an angle to the planes of their opposed sides, whereby the slabs between the kerfs may be broken down.

3. In a machine for the purpose described, rotating means for cutting kerfs in the mine wall, means rotating concentrically with said first cutting means for cutting lateral breaking grooves at the inner edges of the kerfs at an angle to the planes of their opposed sides, whereby the slabs between the kerfs may be broken down.

4. In a machine for the purpose described, the combination of means for cutting kerfs in the mine wall, and a succession of cutters following said kerf-cutting means for cutting lateral breaking grooves at the inner edges of the kerfs at an angle to the planes of their opposed sides, whereby the slabs between the kerfs may be broken down.

5. In a machine for the purpose described, the combination of means for cutting kerfs in the mine wall, and a succession of cutters following said kerf-cutting means and projecting into different planes of movement, for cutting lateral breaking grooves at the inner edges of the kerfs at an angle to the planes of their opposed sides, whereby the slabs between the kerfs may be broken down.

6. In a machine for the purpose described, the combination of means for cutting kerfs in the mine wall, means for cutting lateral breaking grooves at the inner edges of the kerfs at an angle to the planes of their opposed sides, whereby the slabs between the kerfs may be broken down, and means for throwing the groove-cutting means into and out of operative position.

7. In a machine for the purpose described, the combination of means for cutting kerfs in the mine wall, and means operatively connected to and moving with said kerf-cutting means for cutting lateral breaking grooves at the inner edges of the kerfs at an angle to the planes of their opposed faces, whereby the slabs between the kerfs may be broken down.

8. In a machine for the purpose described, the combination of means for cutting kerfs in the mine wall, means for cutting lateral breaking grooves at the inner edges of the kerfs at an angle to the planes of their opposed sides and means for wedging the slabs between the kerfs apart for breaking them down.

9. In a machine for the purpose described, the combination of rotary means for cutting kerfs in the mine wall, means rotating in an

arc of smaller radius than the arc of movement of the first said means, and means for projecting the second said cutting means into a line of movement of increased radius for cutting lateral breaking grooves at the inner edges of the kerfs at an angle to the planes of their opposed faces.

10. In a machine for the purpose described, the combination of means for cutting kerfs in the mine wall, comprising a series of revolving spider arms and cutters thereon, and means for cutting lateral breaking grooves at the inner edges of the kerfs at an angle to the planes of their opposed faces, comprising spider arms revolving with the first said arms and shorter than the latter, and laterally-projecting cutters on the second said spider arms, movable into arcs of rotation of different radii.

11. In a machine for the purpose described, the combination of means for cutting kerfs in the mine wall, comprising a series of revolving cutters, means for cutting lateral breaking grooves at the inner edges of the kerfs at an angle to the planes of their opposed faces, comprising a series of revolving cutters movable with the first said cutters, and following the same, and projecting at an angle to their plane of revolution, and a wedging breaker succeeding the last said cutters.

12. In a machine for the purpose described, the combination of means for cutting kerfs in the mine wall, comprising a series of revolving cutters, means for cutting lateral breaking grooves at the inner edges of the kerfs at an angle to the planes of their opposed faces, comprising a second series of revolving cutters revolving with the first said series and movable into arcs of rotation of different radii, and projecting at an angle to the planes of their rotation.

13. In a machine for the purpose described, the combination of a shaft, means for rotating the same, a plurality of cutter-carrying frames mounted on, and adjustable longitudinally of, said shaft, cutters secured in each of said frames for forming kerfs in the mine wall, and wedges also secured in said frames for wedging into said kerfs and breaking down the slabs between the kerfs.

14. In a machine for the purpose described, the combination of a shaft, means for rotating the same, a plurality of cutter-carrying frames mounted on said shaft, cutters secured in each of said frames for forming kerfs in the mine wall, and wedges also secured in said frames for wedging into the kerfs and breaking down the slabs between them, and a shoe supporting the lower end of the shaft.

15. In a machine for the purpose described, the combination of means for mining a section of the wall, means for casting

the same to one side of the tunnel, and means for mining another section of the wall and casting the same to the opposite side of the tunnel.

16. In a machine for the purpose described, the combination of a rotating means for cutting kerfs in the mine wall, a wedge rotatable with the first said means, and means for moving said wedge into breaking position in the track of said cutting means through the kerf for breaking down the slabs produced by the kerfs.

17. In a machine for the purpose described, the combination of a truck or carriage having supporting wheels whereby the same may be run into a mine entry or tunnel, a frame pivotally supported on said truck on an axis extending lengthwise of the axes of said supporting wheels, means for adjusting said frame up and down on said pivot whereby it may be made to rise and fall at one end, an upright shaft journaled in the latter said end and supported thereby, cutters secured to and rotated by said shaft in a horizontal plane, and means mounted upon said frame and connected with said shaft for rotating the shaft.

18. In a machine for the purpose described, the combination of means for cutting out a section of the wall of the mine, embodying a rotary table-like member for receiving said section, and a breaking means arranged above said table-like member and traveling in a circle concentric therewith, for breaking down the wall section whereby it is caused to fall upon said table-like member.

19. In a machine for the purpose described, the combination of means for cutting two horizontal kerfs in the mine wall, embodying a table-like member, means for rotating said table-like member continuously in the same direction, and a breaking means following the said cutting means into the kerf cut thereby and traveling continuously about the axis of said table-like member.

20. In a machine for the purpose described, the combination of means for cutting horizontal kerfs in the mine wall, embodying a table-like member rotatable continuously in the same direction for receiving the material cut from the mine wall, and a wedge rotating with said table-like member for entering one of said kerfs and breaking down the section of the wall lying between the kerfs.

21. A mining machine having means for cutting out two sections of the mine wall and keeping the sections separate from one another while being cut comprising in combination means for cutting three horizontal kerfs in the wall of the mine, the lower two cutting means embodying table-like members for preventing the particles of the upper cut from commingling with the particles

of the lower cut, and means for operating the cutting means and for rotating the lower one of said table-like members for conducting the particles of the wall received thereon to the rear.

22. In a mining machine, the combination of means for cutting out a section of the mine wall embodying two table-like members provided with cutters, rotatable disks revolving with said members, means for rotating said table-like members, means for imparting an intermittent rotation to said disks, and cutters mounted upon said disks.

23. In a mining machine, the combination of a table-like member rotatable upon an upright axis, independently rotatable disks revolving with said member, cutters carried by said disks, means for rotating said member and means for intermittently rotating said disks.

24. In a mining machine, the combination of a rotary table-like member, independently rotatable disks revolving with said member, cutters mounted on said disks, a wedging means moving around with said member for entering the cut and breaking down a section of the wall, means for rotating said member and means for imparting to said disks an intermittent rotation.

25. In a mining machine, the combination of a table-like cutter, adapted to cut a kerf in the wall of the mine, a wedging breaking means arranged over said table-like cutter, and means for rotating the table-like cutter and causing the breaking means to revolve.

26. In a mining machine, the combination of means for cutting a plurality of horizontal kerfs in the wall of the mine, one of said kerf cutting means embodying a table-like member for receiving particles of the wall thereon, a wedging breaking means arranged above said table-like member and adapted to enter one of the upper kerfs and break down a section of the wall, and means for causing the said breaking means to revolve above said table-like member.

27. In a mining machine, the combination of means for cutting a plurality of horizontal kerfs in the mine wall, one of said kerf cutting means embodying a table-like member, a breaker, means for rotating said table-like member about an upright axis, and for revolving the breaker concentrically about said axis above said table-like member to cause it to enter one of the upper kerfs and to break down a section of the wall upon the table-like member.

28. In a mining machine, the combination of a kerf cutting means embodying a table-like member having a plurality of circular apertures and independently rotatable disks mounted in said apertures to form a continuation of the surface of said table-like member, means for rotating said table-like member, means for imparting an intermittent

- tent rotation to said disks, a cutting tool carried by one of said disks and a breaking tool carried by another one of said disks.
29. In a mining machine, the combination of two table-like members arranged one above the other on an upright axis, means provided on said members for cutting kerfs in the wall of the mine whereby the section of the wall cut out by said members and means will be received between the members, means for retaining upon the lower one of said members the particles of the wall thus received for a portion of the rotary travel of said members, additional kerf cutting means mounted above said members and rotatable upon the same axis, and means revolving in the same circle as said additional kerf cutting means for entering the kerf cut thereby and breaking down a part of the mine wall.
30. In a machine for the purpose described, the combination of a shaft, means for rotating the same, a plurality of cutter carrying frames mounted on said shaft, cutters secured in each of said frames for forming kerfs in the mine wall, and wedges also secured in said frames for wedging into said kerfs and breaking down the slabs between the kerfs.
31. In a mining machine, the combination of a plurality of continuously revolving cutters revolving about an upright axis and adapted to form simultaneously a plurality of kerfs in the mine wall, and breaker wedges following said cutters and revolving about the same axis, for entering said kerfs respectively and breaking down the sections of the wall between them.
32. In a mining machine, the combination of means for cutting out a section of the mine wall, embodying a table-like member on which to receive said section when cut out, a shield or deflector arranged at the rear of said member on one side thereof for deflecting the material to the other side thereof, and a chute arranged at the latter side for receiving the deflected material.
33. In a mining machine, the combination with a support, of a cutter-carrying arm pivoted to the same, cutting mechanism connected to said cutter-carrying arm, and means for supporting said cutter-carrying arm at various elevations during its rotation about said support.
34. In a mining machine, the combination of an oscillatory cutter arm provided with a cutter adapted to enter the wall of the mine for forming a kerf therein, means for revolving said arm about an upright axis to cause it to sweep through the wall, and means whereby said arm is allowed to descend to a lower level than the kerf after leaving the kerf.
35. In a mining machine, the combination of an oscillatory cutter carrying arm provided with a cutter adapted to enter the mine wall for forming a kerf therein, a horizontal cam for supporting said arm and causing it to assume different planes, and means for causing said arm to revolve about an upright axis.
36. In a mining machine, the combination of an oscillatory cutter carrying arm provided with a cutter for forming a kerf in the wall of the mine, means for causing said arm to revolve about an upright axis, and means for lifting said arm away from the floor of the mine after it leaves said kerf.
37. In a mining machine, the combination of a suitable frame, cutting means carried thereby, and means carried by said cutting means for breaking loose the coal as said cutter advances.
38. In a mining machine, the combination of a suitable frame, cutting means, and jarring mechanism carried by said cutting means.
39. In a mining machine, the combination of a suitable frame, cutting means, and a coal breaking enlargement carried by said cutting means.
40. In a mining machine, the combination of a suitable frame, cutting means, and a wedge carried by said cutting means.
41. In a mining machine, the combination of a suitable frame, cutting means, and a wedge on the lower side of said cutting means.
42. In a mining machine, the combination of a suitable frame, a flat cutter having a curved outer edge, means for driving the same, and means carried by said cutter for breaking loose the coal as said cutter advances.
43. In a mining machine, the combination of a suitable frame, a flat cutter having a curved outer edge, means for rotating said cutter, and jarring mechanism carried by said cutter.
44. In a mining machine, the combination of a suitable frame, a flat cutter having a curved outer edge, means for driving said cutter, and a coal breaking enlargement carried by said cutter.
45. In a mining machine, the combination of a suitable frame, a flat cutter having a circular outer edge, means for driving the same, and means carried by said cutter for breaking loose the coal within the boundary line of said cutter.
46. In a mining machine, the combination of a suitable frame, cutting means carried thereby to make a plurality of slits in the coal, and means carried by said cutting means for breaking loose the coal between said slits.
47. In a mining machine, the combination of a suitable frame, cutting means carried

thereby to make a plurality of slits in the coal, and means for applying a breaking force to opposite sides of the severed section of coal.

5. 48. In a mining machine, the combination of a suitable frame, a cutter, means for rotating same, and wedges on opposite faces of said cutter.

10 49. In a mining machine, the combination with a frame, of cutting means and wedging mechanism mounted thereon to move in concentric circles, and means for rotating said frame together with the cutting means and wedging mechanism.

15 50. In a mining machine, the combination with a frame, of cutting means carried thereby to make a plurality of slits in the coal, and mechanism rotatable concentrically with said cutting means and extending into said 20 slits for breaking loose the coal between said slits.

25 51. In a mining machine, the combination with means for cutting a plurality of kerfs in a mine wall comprising a table like member, means for rotating said member, and breaking means following said cutting means into the kerfs cut thereby and traveling about the axis of said member.

30 52. In a mining machine, the combination with means for cutting horizontal kerfs in a mine wall comprising a table like member rotatable continuously in the same direction, and a wedge rotating with said table like member for entering one of said kerfs and 35 breaking down the section of the wall lying between the kerfs.

35 53. In a mining machine, the combination with a table-like cutter capable of cutting a kerf in the wall of a mine, of wedging 40 breaking mechanism having an axis co-incident with that of the table like cutter, and apparatus for rotating the said cutting means and the said wedging breaking mechanism.

45 54. In a mining machine, the combination of a frame, of cutting means carried thereby to make a plurality of slits in the coal, means also carried by said frame for applying a breaking force to a cut section of coal, the axes of said cutting means and said breaking 50 means being co-incident, and apparatus

for rotating said frame together with the cutting means and breaking means.

55. In a mining machine, the combination of a frame, of a cutter thereon, means for rotating said frame and cutter, and a wedge 55 also on said frame and rotatable therewith concentrically with said cutter.

56. In a mining machine, the combination of means for producing a plurality of kerfs in the material to be mined, and means in the 60 kerfs operating simultaneously with said cutting means for applying a breaking force to opposite sides of separate sections of the material for breaking down said material on both sides of the intermediate kerfs. 65

57. The combination of a rotary cutting mechanism rotatable in a given plane during the cutting operation, means for supporting said mechanism, and means for shifting the plane of rotation of said cutting mechanism 70 during a predetermined portion of its rotary travel.

58. The combination of a plurality of rotary cutting mechanisms operating in superposed planes during the cutting operations, supporting means for said cutting mechanisms, and means for shifting the uppermost and lowermost cutting mechanisms to different planes of rotation while the cutters are not operating upon the material being 75 mined. 80

59. The combination of a plurality of cutting mechanisms rotatable in given separated planes during the cutting operation, a common supporting means for said cutting 85 mechanisms forming a common center about which said cutting mechanisms rotate, and means for shifting the uppermost and lowermost cutting mechanisms into lower and higher planes of rotation respectively during predetermined portions of the strokes of 90 said cutting mechanism.

In witness whereof, I have hereunto set my hand this 2d day of August 1905, in the presence of the subscribing witnesses.

EDMUND C. MORGAN.
